UNITED STATES PATENT OFFICE

IRA W. BURGESS, OF MINDEN, WEST VIRGINIA

ELECTRIC SWITCH

Application filed November 8, 1929. Serial No. 405,707.

This invention relates to an electric switch for use on electric mine locomotives and the like the general object of the invention being to provide magnetic locking means for locking the switch arm in any one of its different positions, the current to the magnetic means being controlled by the controller of the locomotive.

Another object of the invention is to so form the switch that it can be used either as a single pole two-way switch or a three-way one.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a view of the complete device with the cover plate removed.

Figure 2 is a section on line 2—2 of Figure 1.

Figure 3 is a section on line 3—3 of Figure 1.

Figure 4 is a section on line 4—4 of Figure 1.

Figure 5 is a section on line 5—5 of Figure 1.

Figure 6 is a view of the switch arm.

Figure 7 is a section on line 7—7 of Figure 2.

In these views 1 indicates the switch box or casing which is formed with a series of openings 2 for the conductors and which is provided with a removable cover plate 3.

Three terminals 4, 5 and 6 are placed in the casing to which the cables 7 are connected and an outlet terminal 8 is placed in the casing and fastened in the block 9 of conducting material which carries a stationary shaft 10 on which is pivoted the switch arm 11. This switch arm extends through a slot in the top of the casing and has a handle 12 on its outer end and a blade 13 is detachably connected 50 with its inner end so that the blade can be

substituted by a new one when the old one becomes worn.

A washer 14 is pinned to the shaft and rests against the arm with a small washer 15 resting on the first washer. A spring washer 16 is placed between the washer 15 and the nut 17 which is fastened to the shaft by a set screw 18. This arrangement insures the blade properly engaged in the terminals while preventing rotary movement of the washers, and the nut which would be apt to damage the spring washer.

As will be seen the parts of the switch are so arranged that the blade 13 thereof can be brought into engagement with any one of the terminals 4, 5 and 6 so that current will pass from that terminal with which the blade is in engagement through the switch arm and the block 9 to the outlet terminal 8. A spring detent 19 is placed in a recess in the block 9 and engages a recess 20 in the switch arm to yieldingly hold the same in its central position.

A shaft 21 is journaled in the supports 22 in the casing and said shaft has attached thereto the arms 23 to which the pins 24 are connected, these pins passing through holes in a plate 25. These pins are so arranged when they are projected by the rocking of the shaft 21 they will lock the switch arm in either one of its three positions. A spring 26 on the shaft tends to hold the same in a position with the pins 24 out of the path of the switch arm. An armature carrying arm 27 is fastened to the shaft 21 with its armature adapted to be attracted by a magnet 28 in the casing so that when the magnet is energized the shaft will be rocked to project the pins into locking position.

This magnet is arranged in the circuit 29 of the controller 30 of the locomotive or other apparatus with which the switch is used. Thus when the switch arm is moved to close one of the circuits and the controller is moved to open position current will be supplied to the magnet so that the shaft will be moved to project the pins 24 and thus the switch arm will be locked against movement, thereby making it impossible for the switch to arc, which always damages a switch, and some- 100

times destroys them entirely. This arcing often results in burning the operator.

It will of course, be understood that the terminal 5 can be removed so as to make the device a two-way switch. Shields can also be placed wherever desired to protect the operator, one of these shields being shown at 31 on the switch arm.

It is thought from the foregoing description that the advantages and novel features of the invention will be readily apparent.

It is to be understood that I may make changes in the construction and in the combination and arrangement of the several parts, provided that such changes fall within the scope of the appended claims.

What I claim is:

1. An electric switch comprising a casing having a slot in one end thereof, a number of terminals therein, a switch arm pivotally arranged in the casing and having one end extending through the slot therein, a handle on this end, a blade detachably connected with the other end and adapted to engage any of the terminals, a terminal electrically connected with the switch arm and magnetic locking means for locking the switch arm in engagement with any one of the first mentioned terminals.

2. An electric switch comprising a casing having a slot in one end thereof, a number of terminals therein, a switch arm pivotally arranged in the casing and having one end extending through the slot therein, a handle on this end, a blade detachably connected with the other end and adapted to engage any of the terminals, a terminal electrically connected with the switch arm and magnetic locking means for locking the switch arm in engagement with any one of the first mentioned terminals, such means comprising a shaft journaled in the casing, arms on the shaft, pins on the arms for extending into the path of the switch arm when the shaft is moved in one direction, spring means for holding the shaft with the pins in lowered position, another arm on the shaft, an armature thereon, a magnet for attracting the armature and means whereby the current of the magnet is controlled by a controller device on the apparatus with which the switch is used.

In testimony whereof I affix my signature.

IRA W. BURGESS.
